UNITED STATES PATENT OFFICE.

GEORGE STAR, OF DAVENPORT, IOWA, ASSIGNOR OF ONE-THIRD TO MARTIN SILBER-STEIN AND ONE-THIRD TO PHILIP WAGNER, BOTH OF DAVENPORT, IOWA.

CHANGEABLE SIGN.

1,188,695.

Specification of Letters Patent. Patented June 27, 1916.

Application filed October 19, 1914. Serial No. 867,330.

To all whom it may concern:

Be it known that I, GEORGE STAR, a citizen of the United States of America, and resident of Davenport, Scott county, Iowa, have 5 invented a certain new and useful Improvement in Changeable Signs, of which the following is a specification.

My invention relates to changeable signs or bulletin boards in which thin metallic 10 strips or slats, provided with flanges at their edges, are interengaged and suspended one from the other, and have character bearing members hanging from the flanged edges; and the objects of my improvement, are 15 first, to provide a slat or strip of the simplest possible form and of such reduced size that much offal or scrap material can be utilized in its manufacture, and of such simple outline as to come within the product of 20 the simplest forms of crimping or flanging machinery; second, to make possible the use of a very simple character-bearing member consisting of a small strip of sheet metal bent over at one end; third, to provide the 25 necessary recesses, for the ready insertion and removal of the character bearing members, through the association of the interengaging slats rather than in the specific form of slat, and fourth, to provide a structure in 30 which the character bearing members can be suspended from either or both faces, making a double sign board, and without regard to which end of the sign board may be uppermost. I attain these objects by the mechanism illustrated in the accompanying drawing, in which—

Figure 1 is a view in elevation of my improved sign. Fig. 2 is a perspective view of 40 a number of interengaging slats showing character bearing members carried on both faces. Fig. 3 is a cross sectional view taken on lines 3—3 of Fig. 1. Fig. 4 is a perspective view of a character bearing member. Fig. 5 is a cross sectional view taken on line 45 5—5 of Fig. 1.

Referring to the drawing in which similar reference numerals refer to similar parts throughout the several views, 1. 1. represent the channel shaped side members that loosely 50 engage the extremities of the metallic slats 2 2. These slats which may be made of long narrow strips of tin or other sheet metal, consist of the body portion 2^a and the flanges

3. 3. formed by bending the longitudinal edges rearwardly, with the free edges of the 55 flanges brought slightly toward the center line of the body portion. The sign board is assembled by suspending one slat from another through the medium of the edge flanges. This, as clearly indicated in Fig. 2 60 disposes the face or body portion of alternate slats in the same vertical plane producing a double face sign with grooves or recesses between alternate slats. The character bearing members 4 which may consist of 65 flat pieces of sheet metal, have one end flanged similarly in form to the flanges on slats from which they are hung as shown. The channel shaped side members are slipped over the ends of the assembled slats and are 70 secured to the end slats only, by soldering or crimping or any approved manner.

As the contours or forms of both edges of a finished slat are alike and as there always is a space or recess between alternate slats, 75 it is obvious that the sign board can be supported with either end uppermost and yet properly function in sustaining the character bearing members.

The device can be used as shown or may be 80 incased in a frame provided with the usual glass doors. Due to its novel construction it can be projected into a passageway from a post or sidewall and read as approached from either direction, thus performing the 85 duty of two separate boards.

By inserting the finger tips in the recess which intersects the character bearing member, or in the recesses at the top and bottom thereof, these characters can be readily inserted or removed.

In my co-pending application filed July 11th, 1914 Serial No. 850,393 the series was formed by a depression in the slat itself while in the present device it exists by reason 95 of the novel arrangement or association of one slat with the other.

What I claim as new is—

In a device of the class set forth, a pair of vertical edge bars and a series of horizontal 100 slats connected at their ends to said bars, these slats being alike as to size and shape so as to thereby be interchangeable and each slat consisting of a plate having its longitudinal edges bent inwardly to form hook-like 105 flanges, the flanges of adjacent plates being

in overlapping interlocking relation and the slats on one side being reversed with respect to the slats on the other side, thereby forming on each face of the structure a series of spaced channels or recesses, for the purpose herein set forth.

Signed by me at Davenport, Iowa this 14th day of October 1914.

GEORGE STAR.
